ELECTRIC LIGHTING FIXTURE

David J. Biller, St. Louis, Mo., assignor to Day-Brite Lighting, Inc., St. Louis, Mo., a corporation of Missouri

Application December 29, 1941, Serial No. 424,725

15 Claims. (Cl. 240—78)

This invention relates to electric lighting fixtures, particularly lighting troughs for fluorescent lighting fixtures. The invention has for its principal objects to provide a lighting trough having a strong and rigid lightweight metal framework and readily attachable light transmitting panels for closing the openings in said framework, to provide quick detachable means for retaining the side panels in place in the framework and to provide for ventilating said trough. The invention consists in the lighting trough and in the construction, combinations and arrangement of parts hereinafter described and claimed.

In the accompanying drawings, which form part of this specification and wherein like symbols refer to like parts wherever they occur:

Fig. 1 is a perspective view of a lighting trough embodying my invention,

Fig. 2 is a top plan view of said lighting trough,

Fig. 3 is an enlarged vertical cross-section on the line 3—3 in Fig. 2,

Fig. 4 is an enlarged fragmentary vertical cross-section on the line 4—4 in Fig. 2,

Fig. 5 is an enlarged fragmentary vertical cross-section on the line 5—5 in Fig. 2,

Fig. 6 is an enlarged fragmentary vertical longitudinal section on the line 6—6 in Fig. 3,

Fig. 7 is an enlarged fragmentary horizontal cross-section on the line 7—7 in Fig. 3,

Fig. 8 is a perspective view of one of the lower middle rails of the metal framework of the lighting trough,

Fig. 9 is a perspective view of a portion of one of the side rails of said framework,

Fig. 10 is a side elevational view of the lower end portion of one of the lower middle rail supporting brackets of said framework.

Fig. 11 is an inner face view of the portion of the bracket shown in Fig. 10; and

Fig. 12 is a vertical longitudinal section through the upper portion of one of the end panels of said lighting trough.

My lighting trough or channel comprises a metal framework including upper side rails A, end rails B connecting corresponding ends of said side rails, a pair of spaced parallel lower middle rails C, and hangers D depending from said end rails midway of said side rails and supporting the ends of said middle rails. Said lighting trough also comprises transversely bowed sheet plastic light transmitting side panels E that cover the spaces between the side rails A and the lower middle rails C, and molded plastic light trans-

mitting end panels F for closing the ends of said trough.

As shown in the drawings, each of the side rails A of the framework of the lighting trough 5 comprises a rolled metal section of substantially inverted U-shaped section with a plane inner side wall 1 having an outstanding lower marginal flange 2 and with a deeper outer side wall 3 that is longitudinally corrugated to provide longitudinal combined ornamental and stiffening ribs or beads 4. Each of the end rails B preferably 10 comprise metal angles arranged with one flange 5 down and with the other or top flange 6 projecting outwardly. The depending vertical flange 5 of each of the end rails B terminates at its ends 15 in inturned vertical flanges or tabs 7 that seat edgewise on the inwardly extending lower marginal flange 2 of the side rails A and are rigidly secured flatwise to the inner faces of the inner side flanges 1 of said side rails preferably by means of rivets 8 that extend through both side walls thereof. Each of the lower middle rails C of the trough framework is of substantially channel-shaped section, with its web 9 arranged vertically and its flanges 10 and 11 inclined upwardly and outwardly. The bottom flange 10 of each bottom rail is curved upwardly adjacent to the web 9 thereof and terminates outwardly beyond the plane top flange 11 of said rail in an upwardly curled free marginal portion 12.

The hanger D, which depends from each end rail B, comprises a vertical channel arranged with its flanges 14 facing outwardly and with its web 15 rigidly secured flatwise to the outer face of 35 the depending inner flange 5 of said end rail preferably by means of rivets 16. At its upper end, each channel-shaped hanger D abuts against the underside of the outstanding top flange 6 of the end rail 5 to which it is secured and has its web 15 bent horizontally outwardly beyond its side flanges 14 and rigidly secured flatwise to the underside of said top flange of said end rail preferably by means of a rivet 17.

At the lower end of each hanger D, the web 15 45 thereof has its middle portion bent to form an upwardly and outwardly inclined tab or flange 18 and its side portions bent inwardly to form spaced inwardly extending horizontal flanges or tabs 19. The two inwardly extending flanges 19 50 at the lower ends of each hanger D extend into the adjacent ends of the channels of the respective bottom rails C and are rigidly secured preferably by rivets 20 flatwise to the upper surfaces of the bottom flanges 10 of said rails between the webs 9 thereof and the upturned outer side mar-

ginal portions 12 of said bottom flanges. As shown in the drawings, the top flanges 11 of the bottom rails C have arcuate notches 21 formed therein above the flanges 19 that are secured thereto, so that access may be had to the securing rivets 20 for said flanges.

The sheet plastic side panels E of the lighting trough are preformed by heating and have sufficient elastic resilience to recover their shape after deformation without the use of the supporting framework therefor. Said side panels have their upper outer margins disposed within the downwardly opening grooves in the side rails A and their lower inner marginal portions disposed within the channels of the lower middle rails C in edgewise abutting relation to the webs 9 thereof. The sheet plastic side panels E are preferably mounted in the metal framework by inserting the upper marginal portions thereof in the downwardly opening grooves of the side rails A and by snapping the lower inner marginal portions thereof into the outwardly opening channels in the lower rails C after flexing said sheets.

Each of the rigid plastic end members or panels F of the lighting trough is substantially in the form of a hollow half-shell that is shaped to conform to the substantially segmental cross-sectional shape imparted to the trough by the curved sheet plastic side panels E and straight end rails B thereof. The molded plastic end panels F are arranged with their cavities 22 facing inwardly, and the sheet plastic side panels E have their end margins seated in said cavities in lapping relation to the walls thereof. The plastic ends F fit over the end rails B of the framework of the lighting trough and are removably secured to the top flanges 6 of said rails by means of screws 23. The end rails B and the hangers D depending therefrom are disposed in the cavity 22 of the plastic ends F; and said ends are further secured to the framework of the lighting trough by means of screws 24 that extend through openings provided therefor in the outwardly extending flanges 13 at lower ends of said hangers and are threaded into the bottom walls of said cavities.

The plastic members F have anchoring lugs 25 that project from the inner faces thereof at the sides thereof that extend endwise into the grooves in the side rails A and have a snug fit therein. The upper ends of the end closures or panels F have ornamental corrugations or beads 4a that extend horizontally from side to side thereof tops thereof and register with and form a continuation of the ornamental strengthening corrugations or ribs 4 in the outer walls of the side rails B. The outer surfaces of the plastic ends F are also formed opposite the hangers D with central upwardly flaring ornamental ribs 26.

The flanges 18 and screws 24 are located directly back of the hangers D and access is had to said screws through vertical slots 27 in the webs 15 of said hangers. The slot 27 in each hanger D is covered by a quick attachable and detachable metal plate 28, which also serves to retain the lower margins of the plastic side panels E in the channel of the lower middle rails C. Each of the combined cover and retainer plates 28 has a tongue 29 struck from the lower edges thereof that hooks over the lower edge of the vertical slot 27 in the hanger D; and each of said plates is also provided with a snap fastener in the form of a hollow outstanding tube 30 having a slit and rounded end 31 and an annular peripheral groove 32 inwardly of said end adapted to

receive the upper edge of said slot when said tube is forced into the latter. Each of the plates also has feet or lugs 33 at its lower corners that extend outwardly on opposite side edges thereof and seat on the lower inner corners of the plastic sheet panels E just beyond the top flanges 11 of the lower middle rails C and clamp said corners down on the upwardly curled marginal edges 12 of the bottom flanges 10 of said rails. As shown in the drawings, the upper corners of the side panels E are notched, as at 34, to clear the rivets 8 and the lugs 25 of the end panels F, the vertical edges of said notches abutting against said rivets and thus preventing end play of said side panels in the framework. The lower corners of the side panels are also notched, as at 35, to clear the lower ends of the hangers D.

The hereinbefore described lighting trough has numerous advantages. The metal framework is simple and economical and provides a strong and rigid support for the molded plastic ends and sheet plastic sides. The plastic ends may be quickly and easily secured to the ends of the frame; and the plastic side sheets are easily mounted in the framework merely by inserting the upper margins of said sheets in the grooves in the side rails, flexing said sheets and then snapping their lower margins into the channels in the lower rails. The sheet plastic sides are quickly and easily locked in place by hooking the tongues 29 of the plates 28 over the bottom edges of the slots 27 in the hangers D and then snapping the fasteners 30 into engagement with the upper edges of said slots. With the plates thus positioned, the feet 33 thereof bear on the lower corners of the plastic side panels and thus serve to clamp the same in the lower rails. At the same time, these plates also serve to cover the slots 27 and thus prevent light from shining through said slots and forming objectional bright spots on the plastic ends of the lighting trough, the ornamental ribs 26 on the plastic ends serving to diffuse the shadows cast thereon by the hangers D located opposite said ribs. The spaced lower middle rails C of the framework form a longitudinal slot at the bottom of the lighting trough, which slot provides for ventilation and allows insects to drop out of the trough.

Obviously, the hereinbefore lighting trough admits of considerable modification without departing from the invention. Therefore, I do not wish to be limited to the precise construction shown and described.

What I claim is:

1. An electric lighting trough comprising an open framework including longitudinally grooved side and middle rails, end rails connecting said side rails, and hangers depending from said end rails and supporting said middle rails below the level of said side rails, closures for the ends of said framework, said closures being supported by said end rails and hangers, and light transmitting side panels extending from end closure to end closure between said side and middle rails with their longitudinal side margins seated in the grooves therein.

2. An electric lighting trough comprising an open framework including side rails having downwardly opening longitudinal grooves therein, end rails connecting said side rails, a pair of spaced middle rails, and hangers depending from said end rails and supporting said middle rails below the level of said side rails and having outwardly opening longitudinal grooves in their remote sides, closures for the ends of said framework.

said closures being supported by said end rails and hangers, and light transmitting side panels extending from end closure to end closure between said side and middle rails with their longitudinal edges seated in the grooves therein.

3. An electric lighting trough comprising an open framework including longitudinally grooved side rails, end rails connecting said side rails, a longitudinally grooved middle rail, and hangers depending from said end rails midway of said side rails and supporting said middle rail below the level of said side rails, light transmitting end closures for said framework, said closures being secured to said end rails and hangers and having lugs extending into the ends of the grooves in said side rails, and light transmitting side panels extending from end closure to end closure between said side and middle rails with their longitudinal edges seated in the grooves therein.

4. An electric lighting trough comprising an open framework including longitudinally grooved side rails, end rails connecting said side rails, longitudinally grooved middle rails, and hangers depending from said end rails midway of the ends thereof and supporting said middle rails below the level of said side rails, light transmitting closures for the ends of said end framework, said closures being secured to and supported by said end rails and hangers, light transmitting side panels extending from end closure to end closure between said side and middle rails with their longitudinal edges seated in the grooves therein, and quick detachable devices engageable with said hangers and cooperating with said side panels for retaining the latter in the grooves in said middle rails.

5. An electric lighting trough comprising an open framework including side rails of substantially inverted U-shaped cross-section, end rails connecting said side rails, a pair of spaced parallel middle rails of substantially channel-shaped cross-section, and hangers depending from said end rails midway of the ends thereof and supporting said middle rails below the level of said side rails and arranged with their channels facing the direction of said side rails, closures for the ends of said end framework and recessed to receive said end rails and hangers, and light transmitting side panels extending from end closure to end closure between said side and middle rails with their longitudinal edges seated therein and with their ends seated in said recesses.

6. An electric lighting trough comprising an open framework including side rails of substantially inverted U-shaped cross-section, end rails connecting said side rails, a pair of spaced parallel middle rails of substantially channel-shaped cross-section, and hangers depending from said end rails midway of the ends thereof and supporting adjacent ends of said middle rails below the level of said side rails and arranged with their channels facing the direction of said side rails, light transmitting closures for the ends of said framework secured to said end rails and said hangers, light transmitting side panels extending from end closure to end closure between said side and middle rails with their longitudinal edges seated therein, and quick detachable devices located in said trough and engageable with said hangers and cooperating with the middle rail engaging portions of said side panels for retaining said portions therein.

7. An electric lighting trough comprising an open framework including side rails, end rails connecting said side rails, middle rails, and

hangers depending from said end rails midway of the ends thereof and supporting said middle rails below the level of said side rails, closures for the ends of said end framework secured to said end rails and hangers and interlocked with said side rails, and light transmitting side panels extending longitudinally of said trough from end closure to end closure and crosswise of said trough from said side rails to said middle rail with their longitudinal side edges seated in said side and middle rails and with their ends seated in said end closures.

8. An electric lighting trough comprising an open framework including longitudinally grooved side rails, end rails connecting said side rails, and longitudinally grooved middle rails suspended from said end rails below the level of said side rails, closures for the ends of said framework, light transmitting side panels extending from end closure to end closure between said side and bottom rails with their longitudinal edges seated in the grooves therein, quick detachable devices located in said trough and cooperating with said side panels for retaining the latter in the grooves in said middle rails, said end closures comprising rigid molded plastic members and said side panels comprising sheets of plastic having sufficient resiliency to enable said panels to be snapped into said longitudinal grooves of said rail, said middle rails being spaced apart to provide a longitudinal opening in the bottom of said trough.

9. An electric lighting trough comprising an open framework including longitudinal side rails, end rails connecting said side rails, hangers depending from said end rails midway of the length thereof and longitudinally grooved middle rails extending from hanger to hanger with their ends rigidly secured thereto, closures for the ends of said framework, means for securing said closures to said end rails and to the lower portions of said hangers, and side panels extending from end closure to end closure with their longitudinal margins seating in the grooves in said side and middle rails.

10. An electric lighting trough comprising an open framework including longitudinal side rails, end rails connecting said side rails, hangers depending from said end rails midway of the length thereof and a pair of spaced parallel longitudinally grooved middle rails extending from hanger to hanger with their ends rigidly secured thereto, closures for the ends of said framework, means for securing said closures to said end rails and to the lower portions of said hangers, and sheet plastic side panels extending from end closure to end closure with their longitudinal margins seating in the grooves in said side and bottom rails.

11. An electric lighting trough comprising an open framework including longitudinal side rails, end rails connecting said side rails, hangers depending from said end rails midway of the length thereof and a pair of spaced parallel longitudinally grooved middle rails extending from hanger to hanger, said hangers having inwardly extending tabs at their lower end extending into and secured within the grooves of said middle rails, closures for the ends of said framework, means for securing said closures to said end rails and to the lower portions of said hangers, and sheet plastic light transmitting side panels extending from end closure to end closure with their longitudinal margins seating in the grooves in said side and middle rails.

12. An electric lighting trough comprising an open framework including longitudinally grooved

side rails, end rails connecting said side rails, hangers depending from said end rails midway of the length thereof and a pair of spaced parallel longitudinally grooved middle rails extending from hanger to hanger with their ends rigidly secured thereto, closures for the ends of said framework, means for securing said closures to said end rails and to the lower portions of said hangers, sheet plastic side panels extending from end closure to end closure with their longitudinal margins seating in the grooves in said side and middle rails, and retainer plates secured to said hangers and having portions that cooperate with said side panels for retaining the middle rail engaging portions of said side panels in said middle rails.

13. An electric lighting trough comprising an open framework including longitudinal side rails, end rails connecting said side rails, hangers depending from said end rails midway of the length thereof and a pair of spaced parallel longitudinally grooved middle rails extending from hanger to hanger with their ends rigidly secured thereto, said hangers having outstanding flanges at their lower ends, closures for the ends of said framework, means for securing said closures to said end rails and to the flanges at the lower ends of said hangers, sheet plastic side panels extending from end closure to end closure with their longitudinal margins seating in the grooves in said side and bottom rails, said hangers having openings therethrough through which access may be had from the interiors of said trough to the means for securing said closures to said flanges, and plates secured to said hangers and covering said openings and cooperating with said side panels for retaining the middle rail engaging portions of said side panels in the grooves of said middle rails.

14. An electric lighting trough comprising an open framework including longitudinal side rails, end rails connecting said side rails, hangers depending from said end rails midway of the length thereof and a pair of spaced parallel longitudinally grooved middle rails extending from hanger to hanger with their ends rigidly secured thereto, said hangers having outstanding flanges

at their lower ends, closures for the ends of said framework, means for securing said closures to said end rails and to the flanges at the lower ends of said hangers, sheet plastic side panels extending from end closure to end closure with their longitudinal margins seating in the grooves in said side and bottom rails, said hangers having openings therethrough through which access may be had from the interiors of said trough to the means for securing said closures to said flanges, and plates secured to said hangers and covering said openings and cooperating with said side panels for retaining the middle rail engaging portions of said side panels in the grooves of said middle rails, said middle rails comprising channels with bottom flanges that extend beyond their top flanges, and said plates cooperating with said side panels to clamp the same against said bottom flanges.

15. An electric lighting trough comprising an open framework including longitudinal side rails, end rails connecting said side rails, hangers depending from said end rails midway of the length thereof and a pair of spaced parallel longitudinally grooved middle rails extending from hanger to hanger with their ends rigidly secured thereto, said hangers having outstanding flanges at their lower ends, closures for the ends of said framework having ribs thereon opposite said hangers, means for securing said closures to the tops of said end rails and to the flanges at the lower ends of said hangers, sheet plastic side panels extending from end closure to end closure with their longitudinal margins seating in the grooves in said side and bottom rails, said hangers having openings therethrough through which access is had to the means for securing said closures to the flanges at the lower end of said hangers, and plates secured to said hangers and covering said openings, said plates having portions that hook over the bottom edges of said openings, portions that snap beneath the upper edges of said openings, and portions that cooperate with said side panels for retaining the middle rail engaging portions of said side panels in the grooves of said middle rails.

DAVID J. BILLER.
